UNITED STATES PATENT OFFICE

FRANK W. ROLLER, OF EAST ORANGE, NEW JERSEY, ASSIGNOR TO ROLLER-SMITH COMPANY, A CORPORATION OF NEW YORK

CIRCUIT BREAKER

Application filed October 12, 1927. Serial No. 225,613.

This invention relates to circuit breakers, and although some features are desirable in circuit breakers for various uses, the invention is particularly applicable to wall circuit breakers and to the formation of control panels for lighting, motors and other circuits of rooms, offices, residences and the like.

One of the main objects of this invention is to provide a switch of the wall type which will be adapted to be easily inserted and removed from a receptacle, which receptacle may be positioned in the wall before the plastering or finishing thereof and provided with terminals to which the wiring circuits may be permanently connected. After the finishing of the wall, the only remaining step is to insert the circuit breaker mechanism into the box or receptacle and the switch is then ready for use. After installation, this invention has a further advantage that the mechanism may be readily removed for inspection, repair, replacement of parts or for changing adjustments as may be desirable when a different overload current value at which the circuit breaker trips is necessary; and this may be accomplished without disturbing the line wiring connections or other parts carried by the receptacle which may remain permanent.

Another important object is to insure that whenever the handle is released the handle will always assume a position to indicate that the breaker is open or closed.

Another important object of this invention is to provide a circuit breaker of the overload type which will be simple and compact in construction and dependable in operation. An improvement of this character obviously makes it unnecessary to use fuses in the wiring circuits with the inconvenience of their removal and insertion when blown by overload. Another object of the invention is the provision in this type of circuit breaker, of means whereby the circuit cannot be closed and held closed by the operation of the circuit breaker handle when an overload or short circuit condition exists; and by means of this improvement if a user moves the operating handle to close the circuit breaker, it will be automatically opened even though the opera-

tor holds the handle in position to close the breaker. These and other objects of this invention will be understood from the following description and accompanying drawings which illustrate a preferred embodiment 55 thereof.

Fig. 1 is a vertical sectional view of the circuit breaker shown in open position.

Fig. 2 is a vertical sectional view of the circuit breaker shown in Fig. 1 but in closed 60 position.

Fig. 3 is a vertical sectional view taken on line 3—3 of Fig. 1.

Fig. 4 is a horizontal sectional view taken on line 4—4 of Fig. 3.

Fig. 5 is a vertical sectional view taken on line 5—5 of Fig. 2.

Fig. 6 is a vertical sectional view showing the relation of the elements of the circuit breaker when the operating handle element 70 is held in closed position when an overload or short circuit exists.

Fig. 7 is a horizontal sectional view taken on line 7—7 of Fig. 2, and

Fig. 8 is a diagrammatic view showing the 75 circuits.

The breaker is contained within and protected by a casing of metal or other suitable material which is located in an opening in the wall, this casing being positioned before 80 finishing the wall. The outside casing is adapted to receive an insulating box 1 which carries the terminals of the wiring and is adapted to removably receive as a unit the circuit breaker mechanism. The outer portions of the four corners of the box 1 are cut away, as shown in Figs. 3 and 5 to permit the convenient passing of the lead in wires 2 from openings through the back of the metal container box and to the terminal 90 screws 3. The incoming wires and terminals are the upper pair, the lower ones being the outgoing terminals and wires. Each of the upper terminals is at the end of a metal rod 4 which extends inwardly through supporting and insulating material and each rod 4 has extending downwardly from its inner end a terminal plate 5. The two plates thus form the fixed contacts of the breaker. From each of the lower terminal screws 3, a con- 95

tacting rod, similar to rod 4, extends inwardly through the insulating and supporting material, and has a contact plate 6 secured to its inner end and bent to extend outwardly in an opening 7 at one side thereof. The two contact plates 6 are adapted to make electrical connection with corresponding contact plates 8 carried by the insulating support for the circuit breaker mechanism, when the latter is slid into position in the box 1.

The box 1, being thus provided with terminals for the wiring and being provided with contacts engaged by the insertion of the switch mechanism, is adapted to be located in position before the wall is finished and have the wiring permanently connected to the box terminals. Thus the wiring and box or receptacle for the switch mechanism may be installed, completed and tested at one time.

The support for the circuit mechanism is shown formed from a piece of sheet metal having a main plate portion 9 with each upper and lower end bent inwardly and again bent at right angles so as to engage the projecting lips of the metal container box and be removably secured thereto by screws. The plate 9 has secured thereto by screws or other means 10 the L shaped insulating supporting plate 11 for supporting parts of the circuit breaking mechanism to which is secured by the screws 12 the contact plates 8.

The main portion of the supporting plate 9 has two inwardly projecting central wings or legs 13, one at each side, between which is pivoted the shaft 14 which is insulated by bushing 15 of suitable insulating material adapted to rotate with the shaft 14. Manually operating switch handle element 16 of insulating material is attached to and supported on bushing 15. The outer end of the switch handle element 16 projects through an elongated opening 17 in the plate 9. To bias the switch handle element 16 toward its downward position or open position, spiral spring 18 is provided on the bushing 15, one end 19 of which is secured to the switch handle element 16 and the other end 20 bearing on the inner face of the plate 9 as shown in Fig. 5.

The movable element contacts 21 of the breaker are shown of yieldable form, being preferably made up of curved laminated strips. Each of the contacts 21 is carried by a conducting element 22, 22, each of which is pivotally mounted at its lower end on elements 23 and 24 secured to the insulating part 11 with spring elements 25 and 26 tending to bias them toward the plate 9, at opposite sides thereof. The two conducting elements 21 are mechanically connected by an insulating bar or strip 27, as shown in Figs. 1, 2, 3, 5 and 6. The element 23 makes elec-

trical contact with contact 8 through securing screw 28 while element 24 is connected to the corresponding contact 8 by wire 29 passing along the under side of insulating part 11 and secured thereto by screw 30 which is connected to screw 31 by fuse wire 32; screw 32 being connected to element 23 by wire 33.

A U shaped element 34 is mounted on the outer face of the insulating element 27, the element 34 having its two legs projecting outwardly as shown in Figs. 1, 2 and 6. The L shaped rod 35 extends horizontally through the outer ends of the element 34, being pivotally mounted therein. Affixed to the rod 35 is an outwardly projecting arm 36 which arm is pivotally connected with one end of a link 37, the other end of this link being pivotally connected to an extending portion 38 of the pivoted switch element 16. The parts 36 and 37 form a locking linkage of collapsible form. When these linkage parts are approximately in line, or have their middle ends slightly beyond a line passing through the axis of the pivots of the outer ends of the parts 36, 37, they are locked in position and cannot move much beyond this position owing to the link 37 having a tongue 39 which is bent over the top of the arm or link 36 and prevents the linkage from collapsing on one side of the line connecting the pivots to their outer ends, but permits the collapse of the linkage in the opposite direction. In Figs. 1 and 2, the locking linkage is shown in a locked position, whereas in Fig. 6, it is shown in collapsed position. A spiral spring 40 encircles the rod 35 and is connected at one end to the arm 36 and at its other end to one leg of the support 34 and thereby tends to turn the locking linkage to locked position. The element 34 is provided with an upwardly directed portion 41 which contacts with inwardly extending stop rod 42 secured to plate 9 serving as a stopping means when the switch is in an open position as shown in Figs. 1 and 6.

A controlling means for opening the circuit breaker automatically comprises an electromagnet 43 mounted at the rear of insulating plate 11 between the conducting members 22. The electromagnet is mounted on an L shaped support 44 having pivoted at one end the armature 45. The core piece 46 of the electromagnet is reduced in cross section at the top and passes through an aperture in the pivoted armature 45. A stop and adjusting screw 47 is threaded into the reduced section of the core piece as shown in Fig. 3. This screw 47 regulates the distance of the armature from the core piece thus forming a setting means which can be regulated to various overload currents. Lead wire 48 from the electromagnet is connected to screw 49 making electrical connection with

the element 24 while lead wire 50 is connected to screw 51 and the contact plate 8.

Mounted to pivot between the extreme ends of extensions 13 is a shaft 52 which carries a lever 53. The lower end of the lever when the circuit breaker is closed normally engages the loop of spring element 54 secured to the insulating plate 11 by screws 55. In this position the U shaped leaf spring 56 on the shaft 52 contacts with the pin 57 of the handle element 16 and is under tension. In the position of the parts shown in Fig. 2 the spring 56 is under tension so that if the lower end of the lever 53 is released by the electromagnet 43 by the armature 45 forcing sliding rod 58 downwardly which forces the spring element 54 downwardly, the upper end of the lever will be thrown to the left as shown in Fig. 6. The rod 35 is bent downwardly at one side of its support 34 forming the downwardly extending arm 59 and is in the path of the pin 60 carried on the upper end of the lever 53. Thus when the lever 53 is automatically released and the spring 56 throws the pin 60 outwardly, the arm 59 will be turned clock-wise, as well as the rod 35, which results in the locking linkage being turned clock-wise rotating the handle element 16 in counter clock-wise movement opening the breaker as shown in Fig. 1. This will not cause the collapse of the locking linkage but does cause the automatic opening of the breaker. If, however, there is an abnormal current passing through the circuit breaker and the operator holds the handle element 16 in the "on" position as shown in Fig. 6, the rod 58 will be forced downwardly by the electromagnet forcing the spring element 54 downwardly, the upper end of the lever 53 moving to the left. Pin 60 carried on the upper end of the lever 53 is thrown outwardly to turn the arm 59 clock-wise as well as the rod 35 which results in the arm 36 of the locking linkage 36, 37, being turned clock-wise. This will cause the collapse of the locking linkage against the action of the spring 40 and thereby cause the automatic opening of the breaker as shown in Fig. 6. When the operator releases his hold on the handle element 16, the spiral spring 18 will force it downwardly to the "off" position as shown in Fig. 1. Thus it will be noted that the operator cannot hold the breaker in contact when an abnormal current or short circuit exists.

The handle element 16 is provided with an adjustable stop 61 limiting the "off" or closed position thereof. This stop is in the form of an adjustable eccentric or cam secured by a screw 62 as shown in Figs. 1, 2 and 6. The stop rod 42 and the section 41 gauge the extreme open position of the movable contact point.

In operation, the breaker when closed causes the parts to assume the position shown

in Fig. 2, the handle 16 being up. When the breaker is opened manually, the handle is moved to its down position shown in Fig. 1. In this movement and when the handle 16 is lowered from the position shown in Fig. 2, the inner end of the handle element will carry the locking linkage in extended position upwardly and cause its line of action to be carried over the pivot of the handle 16. When this occurs the spring 18 causes the handle 16 to turn and likewise the movable contacting elements of the breaker, throwing them to open position as shown in Fig. 1. As regards the automatic opening, assuming the parts to be in the position shown in Fig. 2, an overload current will cause the electromagnet 43 to draw the armature 45 downwardly pushing rod 58 against spring element 54 until the lower end of the lever 53 is released from the spring element 54. The spring 56 then being under tension, will throw the upper end of lever 53 outwardly and cause the pin 60 to engage the arm 59 and turn the same in a clock-wise direction which will shift the locking linkage from the position shown in Fig. 2 to that shown in Fig. 1 without breaking it, as previously described. This permits the brush pressure and the springs 18, 25 and 26 to throw the movable contacts of the circuit breaker to open position, as shown in Fig. 1, the handle element being moved, as previously described, downwardly to indicate that the breaker is off, or in open position. When in this condition, the handle element remains in its lower position, as shown in Fig. 1. To again close the breaker it is merely necessary to raise the handle to its upper position as shown in Fig. 2. Furthermore, assuming the parts to be in the position shown in Fig. 2 and the operator is holding the handle element 16 in this position, an overload or short circuit current will cause the electromagnet 43 to draw the armature 45 downwardly pushing rod 58 against spring element 54, releasing lever 53. Spring 53 being under a slight tension will throw the upper end of lever 53 outwardly and cause the pin 60 to engage the arm 59 and turn the same in clock-wise direction against the action of spring 40 which will break the locking linkage 36 and 37. This permits the brush pressure and the springs 25, 26, to throw the movable contacts of the circuit breaker to open position as shown in Fig. 6. Upon release of the handle element 16, the spring 18 will force it downwardly to the position shown in Fig. 1, the locking linkage being again straightened out. It will thus be readily seen that the position of the handle element 16 will indicate whether or not the circuit breaker is open or closed.

The plate 9 and parts carried thereby are adapted to be readily inserted in the box 1 and to assume a definite position therein when

secured in place by the screws 63 and inserts 64 set in the box 1. In order to more definitely position and guide the parts when the mechanism is inserted, the box is provided 5 with undercut projections 65 as shown in Figs. 3 and 5 and the insulating part 11 is adapted to serve as a guide and fit between these projections. This insures the contacts 8 properly sliding into engagement with the 10 contacts 6 and likewise insures that all of the parts will assume their proper position in relation to the box 1 and parts carried thereby.

It is apparent that this improvement ful- 15 fills the objects and possesses the advantages already referred to herein and other advantages apparent to one skilled in the art. It will be understood that this invention may be embodied in various forms of construc- 20 tion without departing from the scope thereof.

I claim:

1. A circuit breaker switch comprising a movable switch element, a manually operated 25 element, a locking linkage connecting said manually operated element and said movable switch element, and means for simultaneously opening the breaker and changing said manually operated element to open position 30 upon the occurrence of an overload current without breaking said linkage.

2. A circuit breaker switch comprising a movable switch element, a manually operated 35 element, a locking linkage connecting said manually operated element and said movable switch element, and means for simultaneously opening the breaker and changing said manually operated element to open position 40 upon the occurrence of an overload current without breaking said linkage, said means also being adapted to open said breaker when said manually operated element is held in closed position by the operator.

3. A circuit breaker switch comprising a 45 movable switch element, a manually operated element, a locking linkage connecting said manually operated element and said movable switch element, means for breaking said linkage for causing the opening of the breaker 50 on the occurrence of an overload current when the manually operated element is held in closed position, and means for returning said manually operated element to opened 55 position upon release thereof by the operator.

4. A circuit breaker switch comprising a 60 movable switch element, a manually operated element, a locking linkage connecting said manually operated element and said movable switch element, an electromagnetic op- 65 erated means for breaking said linkage for causing the opening of the breaker on the occurrence of an overload current when the manually operated element is held in closed 70 position, and means for returning said manu-

ally operated element to opened position up- on release thereof by the operator.

5. A circuit breaker comprising a recipro- 75 cating manually operated element, a movable switch element, a locking linkage connecting said manually operated element and said movable switch element, the line of action of said locking linkage adapted to be carried across the pivot of said manually operated element when said element is moved in each of its two directions, and means for moving said manually operated means to open position and to move said locking linkage across the pivot of said manually operated element to open the breaker without breaking said linkage upon the occurrence of an overload current. 80

6. A circuit breaker comprising a recipro- 85 cating manually operated element, a movable switch element, a locking linkage connecting said manually operated element and said movable switch element, the line of action of said locking linkage adapted to be carried across the pivot of said manually operated element when said element is moved in each of its two directions, an electromag- 90 net and means controlled by said electromagnet for moving said manually operated means to open position and to move said locking linkage across the pivot of said manually operated element to open the breaker without breaking said linkage upon the occurrence of an overload current. 95

7. A circuit breaker comprising a recipro- 100 cating manually operated element, a movable switch element, a locking linkage connecting said manually operated element and said movable switch element, the line of action of said locking linkage adapted to be carried across the pivot of said manually operated element when said element is moved in each of its two directions, and means for moving said manually operated means to open position and to move said locking linkage across the pivot of said manually operated element to open the breaker without breaking said linkage upon the occurrence of an overload current, and means for breaking said locking linkage to open the breaker upon the occurrence of an overload current when the said manually operated element is held in closed 110 position. 115
